UNITED STATES PATENT OFFICE.

WILLIAM E. SCHNEIDER AND GUS E. VOELKSEN, OF DAZEY, NORTH DAKOTA.

RUG-BEATER.

1,305,497.

Specification of Letters Patent. Patented June 3, 1919.

Application filed March 8, 1918. Serial No. 221,190.

To all whom it may concern:

Be it known that we, WILLIAM E. SCHNEIDER and GUS E. VOELKSEN, citizens of the United States, residing at Dazey, in the county of Barnes and State of North Dakota, have invented certain useful Improvements in Rug-Beaters, of which the following is a specification, reference being had therein to the accompanying drawing.

10 This invention has reference generally to improvements in that class of inventions known as brushing and scrubbing and more particularly relates to an automatic rug beater.

15 As the primary aim and object, this invention contemplates the provision of novel beating means operatively mounted on a main supporting means and arranged upon opposite sides of a rug or carpet supported 20 between the beating means so as to alternately strike the rug on opposite sides thereof as it is being drawn between the beating means.

25 It is an additional and equally important object of this invention to provide movable rug supporting means for carrying the rug or carpet between the beating arms when they are in actuation so as not to strike the rug continually in the same place and consequently insure of an effective cleaning of 30 the rug.

35 More particularly, the present invention embraces the provision of novel means operably mounted in the main supporting means 40 coöoperating with the resiliently mounted beater arms for normally holding them in spaced relation with each other yet permitting of the arms to alternately move upwardly and strike the rug positioned there-

45 As an additional object this invention includes the provision of novel feeding means operatively mounted on the actuating means of the beating arms for feeding the rug supporting cable so that the rug will be moved while the beating arms are in actuation.

50 As a further aim, the invention consists in the provision of improved means for properly tensioning the rug supporting cable.

55 A more specific object of this invention includes the improved construction of the supporting means, as well as the improved rollers on the arms for coöoperating with the notched disk for producing movement of the arms.

Among the other aims and objects of this

invention may be recited the provision of a device of this character mentioned with a view to compactness, in which the number of parts are few, the construction simple, the 60 cost of production low and the efficiency high.

The invention is clearly illustrated in the accompanying drawings, in which Figure 1 is a side elevation thereof;

65 Fig. 2 is a top plan view of Fig. 1;

Fig. 3 is an end elevation of the invention;

Fig. 4 is a transverse section taken on line 4—4 of Fig. 1 in the direction in which the arrows point;

70 Fig. 5 is a perspective detail of the feeding means for the rug supporting cable;

Fig. 6 is an enlarged fragmentary sectional detail of the means for mounting the cam.

75 Similar characters of reference are employed in all of the above described views, to indicate corresponding parts.

Referring now, more particularly, to the accompanying drawings there is provided a 80 pair of standards 1 and 2, the lower ends of which are connected to the bases 3, the latter having feet 4 depending therefrom. A connecting base plate 5 has its respective ends connected to the under surfaces of the 85 bases to hold them in spaced parallel relation with respect to each other, while a cross bar 6 has its respective ends suitably connected in the standards above the bases while braces 7 have their respective ends connected 90 to the cross bar 6 for assuring of a rigid relation between the parts.

With a view toward providing a rug beating means there is employed a pair of complementary beating arms indicated in their 95 entirety by the numeral 8. The lower ends of the arms are pivotally connected upon opposite marginal edges of the connecting base plate 5 preferably by means of hinges 9. These lower ends of the arms are formed of 100 suitable metal as indicated by the numeral 10 while the upper portions thereof are bent outwardly at substantially obtuse angles as indicated by the numeral 11. The upper or beating ends of the arms are formed of 105 pieces of wire and shaped to provide the outline of a paddle 12.

Suitable resilient means such as coiled springs 13 have their respective ends each connected to one side of the cross bar 6 and 110 to the lower end of the adjacent beating arms. The tension of these springs is such

as to normally hold the arms in close relation with each other in such a manner that the angularly bent portions of the lower ends as well as the paddle shaped upper ends 5 are arranged in spaced parallel relation with each other, while the extreme lower ends diverge toward their pivot points.

Coöperating with the resilient means is the actuating means which in the present 10 instance consist of a shaft 14, the respective ends of which are journaled in a bearing 15 mounted in the standard 2 and in another bearing 16 mounted on the cross bar 3 thus disposing the shaft above the 15 cross bar. A disk 17 is carried by the outer end of the shaft and is provided on its periphery with a notch 18. This disk is disposed transversely between the adjacent faces of the angularly bent ends of the 20 beating arms and incidentally coöperates with rollers 19 journaled on the inner faces of the angularly bent portions 11 on the lower ends of the arms. The springs 13 of course hold the rollers in yielding engagement 25 with the periphery of the disk. The outer end of the shaft may be, and preferably is, squared, as indicated by the numeral 20 to removably receive the crank handle 21. When it is rotated, the shaft 30 will be rotated so that when one of the rollers alines with the notch, it will be forced into the notch, owing to the tension of the adjacent resilient spring 13, which action causes the paddle shaped end 12 on 35 the beating arm to move inwardly and strike the adjacent face of a rug not shown which is adapted to be supported between the arms. By further rotating the shaft, the opposite roller will move into the disk 40 so that the adjacent beating arm will be correspondingly actuated. Of course, the continued rotation of the shaft produces an alternate actuation of the beating arms.

As intimated, improved rug supporting 45 means have been provided. In reducing this feature of the invention to practice, pulley wheels 22 are mounted adjacent the upper and lower ends of each of the standards, while an endless rug supporting cable 50 23 is trained thereabout. The cable is also trained about a large pulley wheel 24 carried by a shaft 25, the respective ends of which are mounted in brackets 26 on the upper base plate 5.

With a view toward providing improved 55 tensioning means for the cable, a threaded shank 27 is mounted in an opening 28 in the base 3 which supports the standard 1 and is adjustably engaged by a nut 29 60 having a handle 30 thereon which serves as a means for adjusting the shank with respect to the base. The outer end of the shank is forked as indicated by the numeral 31 while a pulley wheel 32 is journaled 65 in the fork. The cable 23 is jour-

naled about this pulley wheel and also about another pulley wheel 33 journaled in a bracket 34 which depends from the cross bar 6. By this arrangement it will be appreciated that by adjusting the shank 70 27 with respect to the base, the tension on all the pulley wheels will be consequently controlled. In addition it will be understood that by this tensioning arrangement, the portion of the cable 35 between the 75 two standards is taut so as to support the rug not shown as it is being moved therewith.

For the purpose of providing improved means for feeding the rug supporting means 80 so that the rug supporting means will be actuated simultaneously with the actuation of the beating arms, a ratchet wheel 36 is mounted on the shaft 25 made rigid with the large pulley wheel 24. Coöperating 85 with the ratchet wheel 36 is a bent engaging end 37 of a pawl 38, the inner end of which is enlarged and provided with an opening 39. The opening in the pawl is disposed about a disk 40 eccentrically connected to 90 the shaft 14 and rotatable therewith. Ribs 41 are provided on both the side edges of the periphery of the disk 40 and are in turn arranged in spaced relation with the sides of the pawl to permit of a slight loose 95 movement between the pawl and the disk for the purpose that will presently be appreciated. Suitable resilient means such as a coil spring 42 has its respective ends connected to the pawl and to the cross bar so 100 as to yieldably hold the bent end of the pawl in engagement with the teeth of the ratchet wheel. By this arrangement it will be appreciated that upon rotation of the shaft, by reason of the relation between 105 the pawl and the eccentric disk, the pawl will be alternately moved up and down in a vertical plane and inasmuch as the spring 42 yieldably holds the engaging end 37 of the pawl in engagement with the teeth 110 of the ratchet wheel, the latter will be rotated step by step and thereby act as a feeding means.

In use, assuming that a rug is over the portion 35 of the cable, to beat and clean 115 this rug it is only necessary to rotate the shaft 14 which consequently rotates the notched disk 17. By reason of the fact that the arms are tensioned by the springs 13 so as to be normally drawn toward each 120 other, the rollers riding on the periphery of the notched disk 17 will be pushed into the notch, thus imparting a corresponding motion to the paddle shaped end 12 of each arm enabling the arms to alternately strike 125 the rug not shown upon alternate sides thereof. During this actuation, by reason of the pawl and ratchet mechanism, the cable 23 will be fed to draw the rug between the arms.

It is believed in view of the foregoing description that a further detail description of the operation is unnecessary. Likewise it is believed that the advantages of the 5 invention will be readily apparent.

As many changes could be made in the above construction and many apparently widely different embodiments of this invention could be made without departing from 10 the scope thereof, and it is intended that all matter contained in the above description or shown in the accompanying drawings shall be interpreted as illustrative and not in a limited sense. It is also to be understood 15 that the language used in the following claims is intended to cover all the generic and specific features of the invention herein described and all statements of the scope of the invention, which, as a matter of language 20 might be said to fall therebetween.

Having thus fully described this invention, what is claimed as new and desired to be secured by Letters Patent is:—

1. A device of the character described including a support, an endless rug supporting cable mounted thereon, beating arms connected to the support, a shaft journaled in the support and positioned between the arms, resilient means for normally holding 25 the beating arms in close relation with respect to each other, coactive means on the shaft and on the adjacent faces of the arms for coöperating with the resilient means for allowing the arms to alternately strike a rug 30 adapted to be supported on the table, a pulley wheel over which the cable is trained, a ratchet wheel carried by the pulley wheel, a pawl eccentrically connected to the shaft and engageable with the teeth on the ratchet 35 wheel adapted to be supported on the table, a pulley wheel over which the cable is trained, a ratchet wheel carried by the pulley wheel, a pawl eccentrically connected to the shaft and engageable with the teeth on the ratchet 40 wheel and adapted to be moved up and down during the rotation of the shaft so as to rotate the wheel and feed the cable, and resilient means for yieldingly holding the pawl in engagement with the teeth of the ratchet 45 wheel to facilitate actuation.

2. A device of the character described, including a support, beating arms connected to the opposite sides of the support, resilient means interposed between the support and 50 the arms for normally holding the arms in close relation with respect to each other, rollers mounted on the adjacent faces of the arms, a shaft journaled in the support positioned between the arms, a disk carried by

the shaft having a notch in the periphery 55 thereof whereby when the shaft is rotated the rollers will be alternately moved into the notch in the disk thereby being alternately actuated.

3. A device of the character described, including a pair of standards, bases connected to the lower ends thereof, a connecting base plate between the bases for holding the standards in spaced relation, a cross bar interposed between the standards, a pair of 60 beating arms, means for pivotally connecting the lower ends of the beating arms upon opposite sides of the connecting plates, rollers mounted in the inner faces of the arm, a shaft journaled above the cross bar 65 and through one of the standards, a disk carried by the inner end of the shaft and provided with a notch, coil springs for yieldingly holding the rollers in engagement with the periphery of the disk so that the rollers 70 will be forced alternately into the notch in the disk during the rotation thereof to consequently impart movement to the arms.

4. A device of the character described, including a pair of spaced standards, bases 80 carried by the lower ends thereof, a connecting base plate between the bases, a cross bar between the standards, beating arms, a rotatably mounted shaft, coöperative means on the shaft and on the arms whereby when the 85 shaft is rotated the arms will be actuated, an endless rug supporting cable trained about the upper and lower ends of the standards, a rotatably mounted pulley wheel on the connecting base plate and having a cable 90 trained thereabout, a ratchet wheel carried by the inner face of the pulley wheel, a pawl eccentrically connected to the shaft and engageable with the teeth of the ratchet wheel 95 and adapted to be moved up and down during rotation of the shaft so as to rotate the wheel and feed the cable, a coiled spring for yieldingly holding the pawl in engagement with the teeth of the ratchet wheel to facilitate actuation, and means adjustably 100 mounted in one of the bases for controlling the tension of the cable during the actuation of the device.

In testimony whereof we affix our signatures.

WILLIAM E. SCHNEIDER.
GUS E. VOELKSEN.
